UNITED STATES PATENT OFFICE.

FRANK A. NEUMANN, OF CHICAGO, ILLINOIS, ASSIGNOR TO CASSADY-FAIRBANK MANUFACTURING COMPANY, OF CHICAGO, ILLINOIS, A CORPORATION OF ILLINOIS.

NUTCRACKER.

1,282,278.

Specification of Letters Patent. Patented Oct. 22, 1918.

Application filed October 25, 1917. Serial No. 198,370.

To all whom it may concern:

Be it known that I, FRANK A. NEUMANN, a citizen of the United States, residing at Chicago, in the county of Cook and State 5 of Illinois, have invented new and useful Improvements in Nutcrackers, of which the following is a full, clear, and exact description.

My invention relates to nut crackers, and 10 particularly to the kind employing two corresponding arms or levers pivotally connected together at one end between which the nuts are placed and cracked.

The object of my invention is to provide 15 a link member out of sheet metal which is so shaped that it not only serves as the medium for connecting said arms, but also limits the spread or extent of separation thereof and supplies a pocket for a transversely disposed coil spring that keeps said arms spread apart. This improved construction avoids the necessity of any machine work and is very simple, cheap and durable, substantially as hereinafter fully 20 described, and as particularly pointed out 25 in the claims.

In the drawings:

Figure 1 is a side view of my invention.

Fig. 2 is a transverse section taken on 30 dotted line 2—2, Fig. 1.

Fig. 3 is a vertical section taken on dotted line 3—3, Fig. 2.

Fig. 4 is a top edge view of the same.

Fig. 5 is a plan view of the templet from 35 which the link of said nut cracker is made.

As shown in the drawings, A, A, indicate the two arms or handles of my improved nut cracker. These are suitably designed at one end to enable them to be firmly 40 grasped in the hand, and are connected by my improved link at their other end.

The templet shown in Fig. 5 of the drawings consists of an elongated rectangular piece of sheet metal B, each longitudinal 45 edge of which has a pair of corresponding lugs b, b, (which, as will hereinafter be more fully explained, serve as pivotal lugs) projecting sidewise therefrom at equal distances from the center of length of the templet, 50 and have rectangular tongues a, a, cut in the portions thereof between the transverse planes of said lugs and the ends of the same, which tongues have their free transverse edges 5 of the lugs nearest the ends of the templet.

In shaping the link from this templet the central portion of the latter between the dotted lines c, c, is provided with a transverse groove d, as shown in Fig. 3 of the drawings, and then the portions between 60 said dotted lines c, c, and the ends of the templets are bent down on either side of said groove until they are parallel to each other, thus bringing the flat surfaces of lugs a, a, opposite each other. The flattened 65 ends of arms A, A, are placed between these lugs and are pivotally connected thereto by trunnions e, e, that are, preferably, integral with said flattened ends. The ends of these trunnions are extended through the central 70 openings in said lugs and swaged to form heads that prevent their withdrawal. Groove d not only constitutes the spacing element between the sides of the links, but its end edges constitute abutments against which the 75 inner portions of the edges of the arms extending beyond the trunnions bear when said arms have spread apart the desired distance, and thus limit the extent of said spread.

At the time the templet is stamped out 80 the tongues a, a, are bent inward and the ends of the templet are also bent in the same direction. Thus when the portions of the templet forming the sides of the link are brought opposite to each other in parallel 85 relation, the said tongues and the lower edges of the link form a transverse somewhat tubular shaped seat in which a coiled expansion spring D is placed, whose length is such that its ends extend beyond said seat 90 and, when the parts of the nut cracker are properly assembled, press outward against said arms A, A, and are adapted to return said arms to their separated positions after they have been squeezed out. 95

What I claim as new is:—

1. A nut cracker comprising two arms, and a link formed from a rectangular sheet metal templet, each longitudinal edge of which has a pair of lugs projecting therefrom and is provided with a central transverse groove between said lugs which latter when the portions of the templet on each side of said groove are bent parallel to each other constitutes the lugs to which the corresponding ends of said arms are pivotally connected. 100

2. A nut cracker comprising two arms, a link consisting of a single strip of sheet metal bent double to the extended ends of 110

the sides of which the corresponding ends of said arms are pivoted and have a limited outward movement, and a coil expansion spring in the crotch of the nut cracker the 5 ends of which press outward against said arms; the lower edges of the sides of said link being bent toward each other and the sides thereof provided with tongues that are bent inward and together with said lower edges of the link form a retaining seat for said spring.

3. A nut cracker comprising two arms, a link consisting of a single piece of sheet metal and provided with a lengthwise 10 groove in the bend thereof and with pivotal lugs extending from the end edges of the

parallel sides between which the corresponding ends of said arms are pivoted, and a coil expansion spring in the crotch of said nut cracker the lower edges of the sides of 20 said link being bent toward each other and the sides thereof provided with tongues that are bent inward and together with said lower edges of the link form a retaining seat for said spring.

In witness whereof I have hereunto set my hand this 16th day of October, 1917.

FRANK A. NEUMANN.
